UNITED STATES PATENT OFFICE.

EUGENE F. OLSEN, OF ADRIAN, MICHIGAN, ASSIGNOR TO ANCHOR CONCRETE MACHINERY CO., OF ADRIAN, MICHIGAN, A CORPORATION OF MICHIGAN.

PLASTIC-MATERIAL MOLD.

Application filed May 24, 1926. Serial No. 111,187.

This invention relates to casting or molding apparatus.

This invention has utility when incorporated as an ejector of a formed article from 5 a mold together with features of such mold.

Referring to the drawings:

Fig. 1 is a front elevation, with parts broken away, of an embodiment of the invention in molding apparatus as for so-called cement or concrete blocks;

Fig. 2 is a view of the apparatus of Fig. 1 from the left, parts being removed;

Fig. 3 is a plan view of the apparatus of Fig. 1, with parts broken away;

Fig. 4 is a section on the line IV—IV, Fig. 3;

Fig. 5 is a section on the line V—V, Fig. 4; and

Fig. 6 is a lay-out showing the sequence 20 for travel of the pallet as actuated by the rock lever.

Main frame 1 is shown as having therefrom strut 2 for table 3, as a rest, for guide or funnel 4 having handle 5 which may be 25 grasped in shifting such funnel 4 from the table 3 into position over mold pocket 6 formed by end finishing plates 7 as backed by opposing mold walls 8. Between these plates 7 of the opposing mold walls 8, extend plates 9 backed by connecting mold walls 10. The end mold walls 8 terminate in ledges or lugs 11 which may be abutted by shims 12 of selected sizes or extent for thereby adjusting the spacing between the 30 inner connecting plates 9 and thus determine the dimension for the casting or block. These block walls are further assembled by bolts 13, while bolts 14 anchor the end mold walls 8 with the main frame 1. Additional 35 bolts 15 in the frame 1 carry cross portions 16 below the mold side walls 7, 9. These cross portions 16 have bolts 17 therein, the height of which may be adjusted by washers 18, as shims, in providing the desired position 40 for a transverse side of pallet 19 having openings 20 through which core elements 21 may extend in their mounting on the cross portions 16.

The loose or semi-plastic material, as 50 moistened cement and sand, is dumped in the funnel 4 and shaken down or tamped to fill the region above the pallet 19 in this mold. As such filling operation is completed, the handles 5 may be grasped and the funnel 4 shifted laterally to have its plate ledge 22,

as extending toward the forward portion of the machine, act as a trowel in smoothing off the top of the casting or form.

The next operation is the removal of such formed plastic material from this open top 60 mold. This operation is one which should occur without jar, as the freshly formed material is quite fragile before it is allowed to set. Furthermore, the tamping or packing of this material into the mold to give it 65 close grain at the side portions of the mold, as well as about the core to have uniform strength throughout, means that there is considerable adherence between the plates 9, the core 21, and the material of the casting 70 or block. It is true these faces may be coated with a substance to detract from or reduce such adherence. Accordingly, to start this block upward out of the mold, there is considerable resistance. It is desirable that, 75 in overcoming such resistance, the release of the block not result in a quick ejection thereof to throw it out and shatter such block. To this end, in the disclosure herein, there is provided a considerable power multiplication for overcoming the inertia and adherence at starting with a distribution of the power required for maintaining the travel in such a way that the velocity of upward lift of the block in ejection from the 80 mold may occur quite rapidly, but at a non-uniform rate, the speed being a maximum in the intermediate position with a rather quick but slight slow down at the upper terminus of the lift, there to come into locked 85 position so that there may not be a jar in loosening the block from the mold. To this end, rock arm or operating lever 23 is mounted on rock shaft 24 mounted in bearings 25 carried by the frame 1. This shaft 90 24 is parallel to the pallet 19 and slightly forward from the medial vertical plane through such pallet or the mold. This shaft 24 has mounted thereon eccentric toothed member having short radius portion 26, as 95 the starting region with extension therefrom to longer radius toothed portion 27. This short radius portion 26 is in mesh with long radius toothed portion 28 continuous to short radius toothed portion 29 of companion eccentric gear segment fixedly mounted on rock shaft 30 in bearings 31 parallel with the shaft 24 and herein slightly below such shaft 24. This shaft 30, near each end thereof, has fixed therewith de- 100 105 110

pending crank arms 32 from which upwardly extend bent links 33 to crossheads 34 having fixed therewith guide sleeves 35 about guide rods 36 partially housed by ribs 37 in the ends of the frame or base 1. Between these crossheads 34, extend bars 38 having parallel vertical openings 39. Rods 40 adjusted by nuts 41 threaded thereon and having washers 42, may nicely determine the vertical adjustment of these rods 40, as extending upward past the cross portions 16 toward the pallet 19. These rods 40 mounted in the various openings 39 have clearance as to the cross portions 16 and the cores 21. 5

15 In practice, these rods 40 should be just clear of the pallet 19 so that in the tamping operations, the load of such tamping may be directly taken by the bolts 17 and not be transmitted to this ejector device. As the 20 dampened cement and sand has been dumped into place to fill the mold and there has been trowelling of the top thereof by shoveling the funnel 4 with its extension 22 from position over the mold, the handle 25 23 may be grasped by the operator and pulled through an arc herein shown as approximately 90°. This gives a mechanical advantage of speed reduction shown as about two to one between the rock shaft 24 and the 30 rock shaft 30 at the short radius toothed portion 26 as coaxing with the long radius toothed portion 28. At this point, the crank 32 is in its lower position and, accordingly, its lift action through the links 33 and the 35 crossheads 34 is for slow speed rise. This gives not only the speed reduction of the transmission pair of eccentric segments, but also the speed reduction in starting from the arc throw position of the crank 32 at the 40 region of minimum lift component. As the arm 23 is brought forward, there is a uniform variation in the transmission action of the eccentric toothed segments working to increase the lineal travel rate for the crossheads 34 simultaneously with the increase in the vertical lift component of the links 33. 45 This action as to both of these speed reduction devices or speed varying means in the transmission train, herein shown in series, 50 work together for a very rapid building up of the lineal travel rate of the crossheads 34, working as a unit. This building up of the devices as for supplementing each other for a ratio of approximately one to one speed between the rock shafts 24, 30, at which position the cranks 32 are in the region of maximum lineal upward travel rate, and accordingly approximately horizontal. From such point, the links 33, tend to reduce the lineal 55 travel rate, while the lineal travel function of the eccentric toothed members still tends to increase favorably to building up the rock travel rate of the shaft 30 relatively to the rock travel rate of the shaft 24. Resultantly, 60 65 this is a rocking of the shaft 30 through

greater arc than the rocking of the driving shaft 24. In this swing beyond the horizontal position for the cranks 32, and upward therefrom, there is a reduction in the lift lineal travel rate of the crossheads 34, 70 so that as the toothed member 28, 29, reaches its fully thrown position to strike adjustable abutment 43, the rods 40 have ascended such distance as to lift the pallet 19 at least flush with the top of the mold and in about the 75 plane of the table 3, so that the pallet 19 may be removed to take with it the casting and another pallet dropped into position in the mold say on the vertical rods 40 and the lever 23 rocked rearwardly to lower such pallet to rest upon the bolts 17, and the structure is in position for a repetition of this 80 cycle of operations in the production of cast or molded articles. The block as removed may be allowed to set, season, or dry as may be desirable for a completion of the article as an article of building material or commerce. 85

What is claimed and it is desired to secure by United States Letters Patent is:— 90

1. A mold having sides providing forming surfaces for the lateral face of an article, a transverse side, said mold having an opening opposing said transverse side, and an actuator for the transverse side including a thrusting member for said side, a rock arm, and a pair of variable angular velocity transmission device therebetween in series. 95

2. A mold having sides providing forming surfaces for the lateral face of an article, a transverse side, said mold having an opening opposing said transverse side, and an actuator for the transverse side including a thrusting member for said side, a rock arm, and a pair of variable angular velocity transmission devices therebetween in series, one continuously operating from adjacent a terminal position, and the other oppositely operating from an intermediate position. 100

3. A mold having sides providing forming surfaces for the lateral face of an article, a transverse side, said mold having an opening opposing said transverse side, and an actuator for the transverse side including a thrusting member for said side, a rock arm, and a pair of variable angular velocity transmission devices therebetween in series, one comprising a pair of eccentric toothed members. 110

4. A mold having sides providing forming surfaces for the lateral face of an article, a transverse side, said mold having an opening opposing said transverse side, and an actuator for the transverse side including a thrusting member for said side, a rock arm, an eccentric toothed drive member mounted thereon, a follower eccentric toothed member, a shaft therefor having its axis fixed laterally of said rock arm axis, a crank for said shaft, and a connection to said thrust mem- 115 120 125 130

ber movable from one side of said shaft axis to the other side of said shaft axis.

5. A mold having sides providing forming surfaces for the lateral face of an article, a transverse side, said mold having an opening opposing said transverse side, and an actuator for the transverse side including a thrusting member for said side, a rock arm, an eccentric toothed drive member mounted there-

on, a follower eccentric toothed member, a shaft therefor having its axis fixed laterally of said rock arm axis, a crank for said shaft, and a link connection to said thrust member movable from one side of said shaft axis to the other side of said shaft axis. 15

In witness whereof I affix my signature.

EUGENE F. OLSEN.
